SUPERHETERODYNE RECEIVING CIRCUIT

Bernhardus Gerhardus Dammers and Abraham Gertrudus Wilhelmus Uitjens, Eindhoven, Netherlands, assignors to Hartford National Bank and Trust Company, Hartford, Conn., as trustee

Application June 28, 1952, Serial No. 296,215

Claims priority, application Netherlands July 2, 1951

4 Claims. (Cl. 250—26)

The invention relates to superheterodyne receiving circuits of the kind in which use is made of a mixing tube acting as an oscillator by reason of an inductive coupling between an inductor of a tuned local-oscillator circuit in the circuit of a current-conveying electrode of the mixer and a feedback coil included in the circuit of a control-grid of the tube, the intermediate-frequency oscillations being taken from an impedance included in the anode circuit of the mixer. If the incoming signal oscillations and the local oscillations produced by the mixer itself occur on the same control-grid the mixer acts as an additive mixer.

Additive mixing circuits in general and self-oscillating additive mixers in particular have a limitation in that it is difficult to prevent undue coupling between the circuit tuned to the local oscillations and the aerial circuit, so that there is always a certain radiation of the local oscillations from the aerial. If a screen-grid tube is employed as a mixer and the screen-grid has a certain voltage of the frequency of the local oscillations, as is the case with several known arrangements, there is a further limitation in that the conversion conductance is comparatively low. This is due to the fact that the voltages of local-oscillator frequency occurring at the anode and at the screen-grid are in phase opposition to the local-oscillator voltage at the control grid, so that "de-mixing" occurs.

The invention has for its object to mitigate these disadvantages.

According to the invention a superheterodyne receiver in which use is made of a mixing tube acting as an oscillator by reason of an inductive coupling between an inductor of a tuned local-oscillator circuit in the circuit of a current-conveying electrode of the mixer, and a feedback coil included in the circuit of a control-grid of the tube, the intermediate-frequency oscillations being taken from an impedance included in the anode circuit of the tube, is characterized in that the incoming signal oscillations are supplied to a tapping point, for example the centre, of the feedback coil and the said current-conveying electrode is connected to a tapping of the inductor of the circuit tuned to the local-oscillator frequency.

If the mixer employed is a tube comprising a screen-grid, the screen-grid is preferably connected, for high-frequency currents, to the second-mentioned tapping. A very advantageous circuit-arrangement is that in which both the screen-grid and the anode operate as oscillator electrodes and are connected to the said tapping.

Since with the use of the invention in the manner just stated a lower oscillator voltage prevails at the screen-grid than is the case with a connection of the screen-grid to that end of the circuit tuned to the local-oscillator frequency which is not earthed, de-mixing is reduced. This is also the case if the anode is connected to a tapping of the said circuit. Moreover, a favourable internal mixer resistance is obtained at the same time.

With an additive mixing arrangement it has been suggested to reduce the radiation of oscillations of local-

2

oscillator frequency from the aerial by connecting the aerial circuit to the centre of the feedback coil and by connecting that end of the feedback coil which is not connected to the control-grid of the mixer to a point of constant potential through a capacitor. Thus a bridge circuit is obtained, comprising the two parts of the feedback coil, the input capacity and the said capacitor connected between the coil and the point of constant potential. If this bridge circuit is balanced, no voltage of oscillator frequency should occur at the centre of the feedback coil.

It has been found, however, that the use of this known arrangement does not always lead to reduction of the oscillator radiation below the permissible value. This is due to the fact that the circuit coupled with the feedback coil is not symmetrical and that, consequently, the equilibrium of the bridge is disturbed by the parasitic capacities prevailing between the feedback coil and the coil of the said circuit.

When using the invention, it is found that when incorporating such a bridge arrangement a much greater reduction of the oscillator radiation may be obtained. This is due to the fact that the symmetry of the oscillator circuit with respect to the feedback coil is improved, whilst moreover, the oscillator voltage at the coil of the circuit is lower.

With oscillator circuit-arrangements in which the anode circuit of the anode of a receiving tube includes a circuit tuned to the frequency to be produced and in which the grid circuit comprises a feedback coil, it is known to connect the anode to a tapping point of the inductor of the tuned circuit. This measure has for its object to reduce the effect of the prevailing parasitic capacities on the tuning of the circuit. However, with the reception of oscillations in the medium-wave range this effect may be completely neglected with mixing circuit-arrangements. With the circuit-arrangement according to the invention the object of an apparently analogous measure is therefore quite different.

In order that the invention may be more clearly understood and readily carried into effect, it will now be described more fully with reference to the accompanying drawing, wherein:

Fig. 1 shows a first embodiment, and
Fig. 2 shows a slightly modified embodiment.

Referring to Fig. 1, 1 designates an aerial circuit which is inductively coupled with an input circuit 2, tunable to the frequency to be received. The circuit 2 is connected to earth at one end and is connected at the other end through the parallel combination of a resistor 3 and a capacitor 4 to the centre of a coil 5. One end of the coil 5 is directly connected to the first control-grid 9 of a mixer 6 and the other end is connected to earth through the parallel combination of a resistor 13 and a capacitor 14. The elements 3 and 4 operate as a grid leak and a grid capacitor respectively for the tube 6 which acts as an additive mixer.

The coil 5 is inductively coupled with the coil 17 of a circuit 17, 18, 19 tuned to the local-oscillator frequency and acts as a feedback coil. In this circuit capacitor 18 is a tuning capacitor gauged to the capacitor of circuit 2 whilst the capacitor 19 which is fixed or semi-variable, is a padding element to obtain a substantially constant frequency difference between the oscillator circuit and the input circuit.

The two halves of the coil 5 constitute a bridge-circuit in conjunction with the parallel combination of the resistor 13 and the capacitor 14 and with the input impedance of the tube 6, to which the said parallel combination is equivalent. If the bridge is balanced, no oscillations of the local-oscillator frequency should occur across the circuit 2 and thus the aerial circuit.

However, it is found that with known bridge arrangements the freedom from radiation is not generally sufficient, which is due to the fact that the oscillator circuit is connected on the one hand to the anode or to a screen-grid of the tube and on the other hand to earth, so that there cannot be true symmetry. The parasitic capacity between the parts of the feedback coil 5 and the oscillator coil disturbs the bridge equilibrium.

A further disadvantage of certain known additive-mixing arrangements is that "de-mixing" occurs owing to the voltages of further tube electrodes being in phase opposition to the grid voltage.

According to the invention, in order to obviate the said disadvantages, that positive electrode of the tube 6 whose circuit includes the oscillator circuit is not connected to the end of the inductor 17 of this circuit, but to a tapping 24 thereof, for example, the centre. Thus, the voltage of oscillator frequency at the said positive electrode of the tube is lower, so that de-mixing is reduced, whilst at the same time the symmetry of the inductor 17 with respect to the feedback coil 5 is improved.

In the embodiment shown in Fig. 1 the anode 8 of the mixer 6 is connected to a circuit 15, tuned to the intermediate frequency and forming with a second tuned circuit 16 an intermediate-frequency bandpass filter, as well as to the said tapping 24 of the inductor of the oscillator circuit and at the same time interconnected screen-grids 10 and 12 within tube 6 are connected through a capacitor 20 to the said tapping. The screen-grids are, moreover, connected through a supply resistor 21 to the positive terminal of the supply source. The anode is fed through the lower part of the coil 17 and through resistor 23 from the same source. Capacitor 22 provides a high-frequency earth connection for the lower end of 17. In this arrangement the two screen-grids operate, together with the anode, as oscillator electrodes for the local oscillation, which has the additional advantage that automatic gain control may be obtained in a simple manner by means of a control grid 11 placed between the two screen-grids. In the absence of a signal the control-grid has, at the most, a slightly negative voltage with respect to the cathode 7. The control-voltage may be derived, in known manner, from the intermediate-frequency signal so that it varies with the mean carrier-amplitude thereof. The control-voltage exerts substantially no influence on the oscillator operation of the tube, since the grid 11 operates as a distributing grid and the total cathode current remains substantially constant during control.

Fig. 2 shows a second embodiment, which is distinguished from that shown in Fig. 1 in that the screen-grids and not the anode are connected to the tapping 24 of the inductor 17, the anode of the tube being connected through the intermediate-frequency circuit 15

5 to the "live" (i. e. unearthed) end of the circuit tuned to the local frequency. As an alternative, though this is less advantageous, the screen-grids may be connected to the upper end of the said circuit and the anode alone to a tapping of the coil.

With the arrangements described satisfactory conversion conductance is obtained and the radiation of the oscillations from the aerial, at least in the medium-wave region, may be readily reduced to below the permissible limit.

What we claim is:

1. A converter for combining an incoming electric wave with local oscillations to produce an intermediate-frequency wave, comprising an electron discharge tube having a cathode, a control grid, a screen grid electrode and an anode electrode, means to generate local oscillations comprising a tapped inductor, means for electrically connecting an end of said inductor to said cathode, first and second terminals connected to the tap and the remaining end of said inductor, respectively, a tuning capacitance connected between said cathode and said second terminal, said inductor and capacitance providing a resonant circuit tuned to the frequency of said local oscillations, means electrically connecting a first one of said electrodes to said first terminal, means electrically connecting another of said electrodes to one of said terminals, a tapped feedback coil inductively coupled to said inductor and having the ends thereof connected electrically to said cathode and said control grid, respectively, thereby providing feedback to sustain the local oscillations, means connected to apply said incoming wave between the tap on said feedback coil and said cathode, and means coupled to said anode electrode to derive said intermediate-frequency wave therefrom.

2. A converter as claimed in claim 1, in which said first electrode is said screen grid.

3. A converter as claimed in claim 2, in which said anode is connected for high frequencies to said first terminal.

4. A converter as claimed in claim 1, in which said means to derive said intermediate-frequency wave comprises a transformer having a primary winding connected directly in series with said anode.
